(57) CLAIM

The ornamental design for a laser level, as shown and described.

DESCRIPTION

FIG. 1 is a top plan view of an embodiment of a laser level according to the invention.

FIG. 2 is a bottom plan view of the embodiment.

FIG. 3 is a front elevational view of the embodiment.

FIG. 4 is a rear elevational view of the embodiment.

FIG. 5 is a left side elevational view of the embodiment.

FIG. 6 is a right side elevational view of the embodiment; and,

FIG. 7 is a top perspective view from the left side of the embodiment.

In the above drawings, any wording or numerals shown therein does not form a part of the invention.
